CLAIM

The ornamental design for a panel cover fastener, as shown and described.

DESCRIPTION

FIG. 1 is a top perspective view of a panel cover fastener; FIG. 2 is a top plan view thereof of the panel cover fastener shown in FIG. 1;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines in the drawings illustrate portions of the panel cover fastener and form no part of the claimed design.

1 Claim, 2 Drawing Sheets
